Specification of Letters Patent. Patented June 28, 1921.

Application filed April 23, 1919. Serial No. 292,076.

To all whom it may concern:

Be it known that we, HOWARD D. HODGE and JOHN G. DUFF, citizens of the United States, residing, respectively, at New York city, in the county of New York, State of New York, and Waterbury, in the county of New Haven, State of Connecticut, have invented certain new and useful Improvements in Registers, of which the following 10 is a specification.

This invention relates to registers of the type suitable for the counting of machine operations.

As is well known in the art, it is desirable 15 to employ counting devices in manufacturing for keeping count of the output of machines, and for similar purposes. There is a great variation in machines in connection with which it is desirable to employ counters, 20 such variation existing in speed, direction, length, frequency and force of the movements of the parts of the machines by which the counting device must be operated in order to make a proper register of production 25 or completed operations. Moreover, there is also a great variation in size, form, location and necessary clearances in the machines and machine parts on which it is desirable to use counters.

As a result of these various conditions the 30 employment of counters in connection with machines heretofore has necessitated a great variety of special applications and special fittings in order to adapt the counter to the 35 respective machines, locations, etc. In fact, this variation in applications of counters has required almost a special form of counter or special form of intermediate operating connection for each kind or part of a machine 40 on which the counter is employed. This has resulted in the necessity for both left hand and right hand counters, different counters for different directions or speeds of the stroke of the operating mechanism, special 45 modifications for accommodating differences in the length of the stroke of the operating part, and numerous other variations. As a result, in almost every case the installation of the counter is a matter of special application.

It is a purpose of our invention to obviate these various inadequacies and draw-backs, by the provision of a counter which is practically universal in application.

More specifically stated, it is a purpose of

our invention to provide a counter which may be operated without alteration or without specially fitted connections, by rotary movement, by revolving movement, by articulate oscillatory movement, by reciprocating movement, in fact by any kind of movement in any direction.

It is also a purpose of our invention to provide a counter which, without special application, may be operated by any speed 65 of practical mechanical movement.

It is a further purpose of our invention to provide a counter which is operable only by operation of the machine to which it is attached and which cannot be operated spuriously to accomplish registration beyond 70 the actual operation of the machine.

It is a further purpose of our invention to provide a counting device which requires 75 absolutely no intermediary operating connection, but which is adapted for direct connection with the part relied upon to effect the operation of the counter.

It is a further purpose of our invention to provide a counting device which is operable to accomplish accumulation and registration by movement in either of opposite 80 directions, and which cannot be operated by a reversal of the machine to cause subtraction from the amounts already accumulated in the register.

It is a further object of our invention to provide a counter which may be disabled when desired in order to permit the movement of the operating machine for the purpose of setting, etc., without necessitating the disconnection of the counter from the machine in any manner.

A further object of our invention is to provide a counter which requires the fewest 95 and simplest parts, which is strong and durable, which is amply protected from injury, and which is easily accessible for the purpose of setting or resetting, yet may be sealed against unauthorized access, and 100 which is compact, sightly, and easily read.

Still further objects of our invention will be obvious upon an understanding of the device as pointed out in the following description and claims, reference being had to 105 the accompanying drawings forming a part of this application, and in which Figure 1 represents a front view of the counter partly in section and with parts of the casing broken away.

Fig. 2 is a section substantially on line 2—2 of Fig. 1.

Fig. 3 is a perspective illustration of the operating weight or inertia element,

Fig. 4 is a detail in the nature of a section on line 4—4 of Fig. 2,

Figs. 5, 6, 7, and 8 are diagrams illustrating movements which the counter is adapted to register.

These illustrations show what we regard as the preferred form of the device, and it is quite obvious that the invention is susceptible of a variety of embodiments differing in various particulars from the form illustrated.

Referring to the illustrations by means of the reference numerals applied, it will be understood that the numeral 1 designates a frame-plate, circular in the form shown, but not necessarily of that contour, upon which is mounted an accumulator frame 2. At its outer extremity the accumulator frame supports an end frame 4 which, together with frame 1 furnish bearings for register shaft 5, which is rotatable. Register shaft 5 extends through the frame-plate 1 and has fixed to its end a ratchet-wheel 6, the connection being such that the rotation of ratchet-wheel 6 will rotate shaft 5. Fixed for rotation with shaft 5 by means of the pin collar 7 is a units counting wheel 8 provided with indicating characters on its periphery, comprising the numerals "1" to "9" inclusive and "0". Freely mounted on shaft 5 is a series of higher order register wheels 9, similarly provided with indicating characters on their peripheries. The units wheel, and each of the higher order wheels, carries a holding disk 10 in which is provided a carrying notch 12, and each of the higher order wheels carries a conjoined actuating pinion 11.

On a rod 14, supported in frame-plates 1 and 4, are mounted a series of carrying pinions 15 of the wide and narrow tooth kind, through the instrumentality of which carrying is accomplished from wheels of lower orders to wheels of next higher orders by means of the carrying notches 12 and pinions 11.

It will be apparent that this is a well known type of cyclometer register of the kind disclosed in the United States Letters Patent No. 217,827 to Stalmann, and it is equally obvious that other types of counting and accumulating mechanisms may be employed for the purpose of registering and indicating the count.

Mounted on the frame-plate 1 in operative association with the ratchet-wheel 6 is a vibrating or oscillatory inertia element, which in the present embodiment is in the form of a reciprocating weight 16. This weight 16 is spaced from the frame-plate 1 by supports 17 which slidably engage the

frame-plate 1, and said weight is held in position by means of the stud-screws 18 seated in the frame plate 1 and having their heads disposed in counter-sunk portions 19 of the slots 20. This oscillatory inertia member is preferably made of material of such sort as to give it considerable weight, and to afford proper free working bearing on the plate 1. Carried by the inertia member is a pair of pallets 21 properly spaced and arranged for coöperation with the ratchet-wheel 6 after the manner of escape-ment pawls so that, upon each complete vibration of the member 16, the ratchet-wheel is rotated to a distance of one tooth, and is retained by the pallets against overthrow or further rotation during intermediate periods. This rotation of ratchet-wheel 6 is induced by the movement of the respective pallets toward the shaft 5 while in contact with the involute or non-radial faces of the ratchet teeth. By such operation the wheel is rotated part of one units distance by one pallet upon the movement of the inertia member in one direction, and the rest of the distance by the other pallet's coöperation upon movement of the inertia member in the reverse direction. Due to the fact that one or the other of the pallets is always interposed between the teeth of the ratchet-wheel, it is impossible for the ratchet-wheel to be rotated in the reverse direction. The rotation of ratchet wheel 6 and register shaft 5 and units register wheel 8 accomplished by one complete vibration of the member 16, 100 is sufficient to advance the units wheel the distance necessary to register and indicate one unit additionally. In such fashion complete vibrations of the member 16 are registered, counted by the units wheel, and accumulated in the high order wheels through the instrumentality of the carrying means.

The arrangement of the oscillatory inertia member 16 is such that it will be vibrated in a manner to actuate the ratchet pinion 6 110 by any form of movement of frame-plate 1 which will displace the center of gravity of the inertia member from its point of rest, which latter is established by suitable stops such as contact of one or the other of 115 pallets 21 with the bottom of a notch of ratchet wheel 6, or of one or the other of screws 18 against the end wall of its associated slot 20; or by any movement on the part of the frame-plate 1 which will overcome the inertia of the member 16. Accordingly, if frame-plate 1 is rotated on a non-vertical axis, (Fig. 5), the member 16 will be given a complete vibration upon each rotation, sliding first in one direction, then 125 in the other, between the limits imposed by the stops as the force of gravity overcomes the friction when the member 16 passes its angle of rest. The same effect is accomplished when the frame-plate 1 is re- 130

volved in a non-horizontal plane, (Fig. 6). When the frame-plate 1 is given a reciprocating or arcuate oscillatory movement substantially in line with the line of movement of the inertia member 16, (Figs. 7 and 8), said inertia member will be vibrated relative to the ratchet-wheel 6, due to its inertia, upon each complete oscillation or reciprocation of the frame-plate. The same effect is accomplished when the frame-plate 1 is revolved in a horizontal plane. By virtue of the form of the ratchet-wheel and the arrangement of the operating pallets, the movement of the ratchet-wheel and consequently of the register shaft, will always be progressive in the direction to accomplish accumulations in the register wheels. Accordingly, the register is operable by movement in either of opposite directions to effect accumulation, and it is impossible to subtract amounts from those accumulated in the register by reversing the movement of the device or the direction of movement of the operating machine part.

In order to effect counting and registration of the operations of a moving machine part, therefore, it is necessary simply to give the frame-plate 1, movement in accordance with the movement of such operating machine part. This may be accomplished by mounting the device upon the moving machine part by means of the screw 22, as indicated in Fig. 1, wherein the movable machine part is designated by the character M. Screw 22 is carried on a drum 24, which is mounted on frame-plate 1 and forms an inclosing case for the operating elements mounted thereon. In order to derive the greatest responsiveness from the oscillatory member 16 in rapid rotating and revolving movements, it is desirable that the attachment 22 be disposed on the axis of vibration of the inertia member. By means of connection 22 the device may be readily mounted on any moving part of the machine from which a proper count of operations may be derived, irrespective of the form of movement of such part. The degree or rapidity of the movement is immaterial so long as the force is sufficient simply to overcome the inertia, or accomplish displacement of the point of rest, of the member 16. The construction and mounting of the oscillatory member 16 in the manner described is such that it has a translocatory movement whereby it is bodily displaced from one locality to another on the frame-plate with a rectilinear movement. This is of particular advantage in several respects. Such a mounting of the oscillatory inertia member permits the effective utilization of its entire weight and the inertia accruing therefrom, as well as its responsiveness to the force of gravity. In this particular it has distinct advantage over a pivotal or

swinging connection, wherein the only efficiently effective weight is that at the end of the pendulum, the material decreasing in effectiveness according as it lies closer to the point of pivotal connection. The sliding arrangement also permits the utilization of a maximum amount of metal in the inertia element for the size of the device. Moreover, it contributes to a very compact construction and arrangement of parts, as it enables the assembling of the inertia element over other operating portions, and requires a minimum degree of movement of the inertia member.

As a means for disabling the counting mechanism without requiring the detachment of the device from the machine, we provide the locking member 25 carried by the sliding plate 26 on the face of frame-plate 1. The plate 26 is movable to two positions by manipulation of the button 27. In one position, as shown in full lines in Fig. 2 the locking member 25 lies in line with one of the slots 20, so that it does not make contact with the inertia member 16 in the movement of the latter to the position indicated by the heavy dot and dash line in said figure. In the other of its positions, that indicated in the dot and dash line in Fig. 2, the locking member 25 is adapted to engage the side of the member 16, when the latter is in the position indicated in the small dot and dash line in Fig. 2, to retain it against vibration. As is shown in Fig. 4, the button 27 is connected with the sliding plate 26 by a connection 28 operating through a slot in the frame plate 1. As shown in Fig. 2, the locking member 25 is retained selectively in either of its two positions by a detent spring 29 arranged for frictional engagement with the sliding plate 26.

A suitable casing in the form of a barrel 30 is arranged to inclose the register. Said casing is provided with a window or sight opening 31 through which may be read the indicator figures on the indicating line of the register wheels. This casing is arranged to fit on a locating disk 32 which is carried on the frame plate 1, and lug 34 is arranged for engagement in a notch in the margin of the barrel to insure proper location of the sight openings on the indicating line. The barrel 30 is held in position by means of a nut 35 seated on the screw 36 which is mounted on the end plate 4. An unauthorized removal of the nut 35 may be prevented by a suitable seal, in the form of a wire or other member passed through the aperture 37 in the end of said screw.

It will be observed that this construction provides a particularly compact and efficient device, the working parts of which are completely protected from accidental or intentional injury or disarrangement, and that the disposal of parts is such as to render

the inspection and reading of the indicators particularly convenient. It will be observed that the indicators face in a direction which is at right-angles to the axis on which the device is mounted, so that they face in a direction in the line of movement of the device when it is supported on a moving machine part. Because of this disposal, the indicators remain in the line of vision of the inspector for a longer period of time than if they faced in a direction transverse of the direction of movement. Hence the reading of the device while it is having either reciprocating, oscillatory or revolving movement is greatly facilitated.

Having thus described our invention, what we claim is:

1. A counting register comprising a frame member, an accumulator carried thereby and comprising co-axially disposed registering elements, an oscillatory actuating member carried by the frame member and movable relative thereto and having oscillatory movement transversely of the axis thereof for actuating the accumulator, and means for affixing the frame member to a movable machine part for movement therewith.

2. In a registering counter, the combination of a frame member, an accumulator, an oscillatory inertia member carried by the frame member and movable in opposite directions thereon by gravity, means for actuating the accumulator to register a unit upon each complete vibration of the oscillatory member, and means for affixing the frame member to an operating machine part to accomplish vibration of the oscillatory member.

3. In combination with a movable frame, an inertia element carried thereby and movable thereon by gravity, an accumulator, op-

erable means whereby said accumulator is actuated to register a unit at each vibration of the inertia element, and operable means for detaining the inertia element 45 against effective movement relative to the frame.

4. In combination with a movable machine part, a casing carried thereby, a vibratory inertia element inclosed therein and having 50 movement relative thereto, an accumulator, means whereby said accumulator is actuated by movement of said inertia element relative to the casing, and means operable exteriorly of the casing for inhibiting movement of 55 the inertia element relative thereto.

5. An operation counter comprising a movable frame, a register mounted thereon, a wheel effective to operate the register additively, an inertia element mounted for reciprocal movement on the frame across the wheel, and means carried by the inertia element and rendered effective upon the wheel by movement of said element in each direction to accumulate a unit in the register upon each complete vibration of the inertia element.

6. An operation counter comprising a movable housing, an inertia element slidably mounted in the housing for movement 70 on a diameter thereof, said inertia element covering substantially the entire area within the housing and having its lateral margins conforming substantially to the contour of the lateral portions of the housing to permit their intimate juxtaposition, registering mechanism associated with the housing, and means for actuating said mechanism by movement of the inertia element in the housing.
